CLAIM

The ornamental design for a strawberry shaped game board, as shown and described.

DESCRIPTION

FIG. 1 is a top, front, right side perspective view of a strawberry shaped game board showing my new design;

FIG. 2 is a bottom, rear, left side perspective view thereof;

FIG. 3 is an enlarged front elevation view thereof;

FIG. 4 is an enlarged rear elevation view thereof;

FIG. 5 is an enlarged left side elevation view thereof;

FIG. 6 is an enlarged right side elevation view thereof;

FIG. 7 is a top plan view thereof; and,

FIG. 8 is a bottom plan view thereof.

The broken lines in the drawings illustrate portions of the strawberry shaped game board that form no part of the claimed design.
